UNITED STATES PATENT OFFICE

CHARLES L. GEORGE, OF FINDLAY, OHIO, ASSIGNOR TO THE BUCKEYE TRACTION
DITCHER COMPANY, OF FINDLAY, OHIO, A CORPORATION OF OHIO

BUCKET CLEANER

Application filed March 21, 1929. Serial No. 348,814.

This invention relates to a bucket cleaner adapted to be used on trenching machines or the like, and more specifically on machines which have an endless series of continuously travelling digging and conveying buckets.

The general object of the invention is to provide improved means for cleaning muck, gumbo or other sticky material from the bucket as the latter is carried past dumping position, and to operate the cleaning means in such a manner as to dislodge practically all of the material, both from the bucket and from the cleaning member. In its present embodiment, the cleaning means comprises a blade which constitutes the back of the bucket and which is adapted to be moved through the bucket to discharge the contents of the latter. In connection with the discharging operation, the blade is flipped back and forth between suitable abutment members to jar and dislodge material which would otherwise be left sticking to the blade.

The invention consists further in various details of construction and combinations of elements which will be more particularly described in connection with the accompanying drawings and subsequently claimed.

In the drawings:

Figure 1 is a side elevation of a portion of a machine embodying the invention, one of the buckets and the corresponding cleaning member being shown in section.

Figure 2 is a section taken on the line 2—2 of Figure 1.

Figure 3 is a perspective view illustrating the manner in which each bucket is mounted.

Figure 4 is a longitudinal sectional view of a portion of one of the endless carriers which support the buckets.

Figure 5 is a detail sectional view taken on the line 5—5 of Figure 4.

Figure 6 is a front elevation of one of the rooters which are used in conjunction with the buckets.

As illustrated in the drawings, the invention is embodied in a trenching machine having a rearwardly and upwardly inclined beam or framework 7 which supports a transverse shaft 8 at its upper end. This shaft is adapted to be rotated by any suitable means

and has a conveyer wheel 9 secured near each end thereof. Each conveyer wheel 9 has a series of arcuate segments 10 alternating with sockets 11, and extending across each of these sockets is a web 12 to which a pair of oppositely disposed teeth 13 are bolted or otherwise secured.

A conveyer chain 14 passes over each wheel 9. Each of these chains is made up of a series of cleaner links 15 which alternate with pairs of connecting links 16. Each pair of connecting links 16 are secured together with bolts 17 or the like and are provided at each end with spaced ears 18 traversed by a pin 19 to which the adjacent link 15 is connected. Each pin 19 is adapted to rock in the ears 18 and has an enlarged central portion 20 which receives the end of the link 15 and which prevents the pin from slipping out through the ears 18.

Each of the links 15 is formed with an extension 21 to which the side of a bucket 22 may be secured, and a shoulder 23, formed on the link, is adapted to seat in a corresponding recess 24 formed in the rear edge 75 of the bucket. Each bucket is formed with a curved bottom 25 with digging teeth 26 suitably secured thereto and projecting forwardly therefrom. Each side of the bucket is formed near its upper end with a bearing 27 adapted to receive a pivot pin or bolt 28 on which a cleaning blade 29 is pivotally supported, and as the blade swings about its pivot, its lower edge follows the arcuate surface of the bottom 25. The rear face of the blade 29 is formed with lugs or ears 30 in which a roller 31 is mounted.

As the bucket travels with the carrier chain 14 in the direction indicated by the arrow in Figure 1, the roller 31 is adapted to ride along a track 32 secured to the upper end of the framework 7. The track 32 is so formed that the blade 29 at first moves rather slowly across the bottom of the bucket until the roller reaches the more sharply curved raised portion 33 of the track. Since the buckets travel quite rapidly, as the roller 31 reaches the raised portion 33, the blade is flipped outwardly rather quickly against the stops 34 which overhang the sides of the bucket. 100

When the blade strikes the stops it rebounds until it is suddenly stopped as the roller again engages a lower part of the track. The track 32 is preferably formed with several of these raised portions 33 alternating with 5 downwardly curved portions so that the cleaning blade 29 is rapidly flipped back and forth several times between the stops 34 and the lower portions of the track, imparting to 10 the blade a series of blows which tend to dislodge any material which might otherwise be left sticking to the blade. The blade, as well as the bucket, is therefore left comparatively clean as the bucket approaches the 15 uppermost part of its path.

In connection with the series of digging buckets, it is also customary to interpose a number of rooter members 35, each of which may be attached at each side of one of the 20 links 15 in the same manner as the digging buckets are attached. As shown in Figure 6, the rooter element 35 is connected at each end to a link 15 by means of a connecting member 36, which is provided with seats 37 and 38 disposed at different angles and having rooter teeth 39 and 40 respectively secured thereto. Each of the teeth 39 and 40 provides clearance for the other and together 25 provides clearance for the other and together 30 material between them may be easily removed by the teeth 26 of the digging buckets.

In the operation of the invention as applied to a trenching machine, the rooter elements 39 and 40 cut the sides of the trench 35 in advance of the digging operation effected by the buckets with their forwardly projecting teeth 26. The angles at which the teeth 39 and 40 are disposed and the manner in which they are mounted greatly facilitate 40 the digging operation. The operation of the cleaning blades in the manner described results in thoroughly cleaning the blades as well as the buckets, each time they pass dumping position, so that the trenching machine 45 may be operated under all conditions with the utmost efficiency.

While I have shown and described in detail what appears at present to be the most desirable embodiment of the invention, it is 50 apparent that various modifications may be made therein without departing materially from the scope thereof as claimed.

What I claim is:

1. In a machine of the class described, a 55 series of buckets, means for causing said buckets to travel in an orbit, a cleaning blade associated with each bucket, and means for quickly flipping each blade several times back and forth across the bottom of the bucket 60 toward the end of each upward flight thereof and stopping the blade with a jar at the end of each movement in either direction.

2. The combination with a series of traveling buckets, of a cleaning blade carried by 65 each bucket, a track adjacent the path of the

buckets, and means on each cleaning blade engageable with the track, said track including a succession of raised portions to cause each blade to move several times across the respective bucket as it travels thereover.

3. The combination with a series of traveling buckets, of a cleaning blade carried by each bucket, a track adjacent the path of the buckets, means on each cleaning blade engageable with said track, said track having 70 sharp undulations to cause the blades to move quickly across the bucket during its travel, and stops connected with each bucket in the path of the blade, against which the blade is suddenly stopped and caused to rebound.

4. The combination with a series of traveling buckets, of a cleaning blade for each bucket movable across the same, a stop limiting the outward movement of the blade, a track, and means on each cleaning blade engageable with the track, said track having a 75 gradually inclined portion for moving the blade slowly across the bucket, followed by sharp undulations for subsequently flipping the blade quickly across said bottom causing 80 it to rebound.

5. In a machine of the class described, a bucket, a cleaning blade pivotally mounted on the bucket and normally constituting a back therefor, a stop limiting the forward movement of the blade, means for moving the bucket upwardly, a track, and a roller carried by the blade for engaging the track, said track having undulatory portions operable to move the blade across the bottom of the 100 bucket as the bucket approaches its uppermost position.

6. In a machine of the class described, a bucket, a cleaning blade pivotally mounted on the bucket and normally constituting a back therefor, means for moving the bucket upwardly, a track, means on the blade for engaging the track, said track having sharp undulations to cause the blade to move quickly across the bottom of the bucket as the bucket approaches its uppermost position, and a stop connected with the bucket and in the path of the blade, against which the blade is suddenly stopped and caused to rebound.

7. In a machine of the class described, a bucket, a cleaning blade pivotally mounted on the bucket and normally constituting a back therefor, a track, means for moving the bucket upwardly adjacent the track, means on the cleaning blade engageable with said track, said track having a gradually inclined portion for moving the blade slowly across the bottom of the bucket, followed by sharp undulations for subsequently flipping the blade quickly across the bottom, and a stop carried by the bucket for suddenly stopping the blade and causing it to rebound.

In testimony whereof I have hereunto signed my name to this specification.

CHARLES L. GEORGE.
